CLAIM

I claim the ornamental design for a multi-sided closure, as shown and described.

DESCRIPTION

FIG. 1 is a front perspective view of the claimed design; FIG. 2 is a bottom perspective view of FIG. 1; FIG. 3 is a front view of 1, the right, back, and left view being the same; FIG. 4 is a top view of FIG. 1; FIG. 5 is a bottom view of FIG. 1; and, FIG. 6 is a cross-sectional view along the plane identified in FIG. 4.

In the drawings, the broken lines show portions of a multi-sided closure that form no part of the claim.
